UNITED STATES PATENT OFFICE.

MEYER ZIMRING, OF BROOKLYN, NEW YORK.

UNDERGARMENT.

1,254,874.

Specification of Letters Patent. Patented Jan. 29, 1918.

Application filed February 26, 1917. Serial No. 150,938.

To all whom it may concern:

Be it known that I, MEYER ZIMRING, a subject of the Czar of Russia, and resident of the borough of Brooklyn, county of 5 Kings, city and State of New York, have invented a certain new and useful Improvement in Undergarments, of which the following is a specification.

My invention relates to undergarments 10 and has for its object to provide a lady's combination undergarment comprising a corset cover or chemise, a petticoat and drawers. My improvement further contemplates constructing the garment with a 15 minimum of seams and so that bulkiness and double thickness of material are avoided, particularly over the hips of the wearer. A further purpose of my invention is to combine the drawers and petticoat in such a 20 manner that the former serve to give a finished appearance to the petticoat. Other objects of my improvement will appear from the description hereinafter and the features of novelty will be pointed out in the appended 25 claims.

Reference is to be had to the accompanying drawings which illustrate an example of my improvement and in which Figure 1 is an elevation of my improved undergarment; Fig. 2 is a detail view with parts broken away; Fig. 3 is a central vertical section and Fig. 4 is a detail sectional view on the line 4—4 of Fig. 1.

As shown in the illustrated example 5 is 30 the chemise or corset cover and 6 is the petticoat, these two elements being formed as a unit and comprising front and rear portions secured together by seams 7, which extend lengthwise of the garment at opposite 35 sides thereof as shown in Fig. 1. The chemise or corset cover 5 is provided with the usual openings 8 and 9 for the accommodation of the neck and arms respectively of the wearer.

The drawers 10 which in the illustrated example are of the envelop type are secured in the garment by the seams 7 and by seams 11, the latter serving to attach the front and rear portions of the drawers to the front and 50 rear of the petticoat as is clearly shown in the drawings. The upper edges of the drawers are cut along curved lines converging toward each other as shown at 12 and in the garment extend upwardly from a point 55 near the bottom of the petticoat to a point in the waist region of the garment as shown

in Fig. 1. The seams 11 accordingly follow these lines so that in the completed garment the drawers extend to the waist line at the center of the garment and double thicknesses of material over the hips are entirely avoided. The envelop drawers are completed by means of the flap 13 which is secured to the rear section of the drawers and is detachably connected with the front section 60 thereof in any suitable manner, as by means of buttons and button holes 14.

In the preferred construction the bottom of the petticoat is circular in form as indicated at 15 while the drawers are of the 70 type known as circular drawers and are constructed and positioned in the garment so as to project beyond said circular edge of the petticoat as shown at 16. With this arrangement the drawers in combination with the 75 lower edge of the petticoat impart a distinctive and ornamental finish to the garment as shown in Fig. 1. The bottom edges of the petticoat and drawers may be suitably finished with lace or otherwise to increase 80 the attractiveness of the garment.

In order that the upper section 5 of the garment may be utilized as a corset cover, said garment is provided at intervals with outwardly extending small folds 17 in which 85 apertures or button holes 18 are formed. The folds 17 are located at intervals approximately along the waist line of the garment and the button holes 18 thereof serve to accommodate a ribbon or the like 19, 90 which serves as a draw-string whereby the garment may be gathered in at the waist line to form a perfect corset cover. When it is desired to wear the garment as a chemise the ribbon 19 is simply permitted to 95 remain slack which leaves the garment in the form shown in Fig. 1. By providing the folds 17 and button holes 18 upon the exterior of the garment the ribbon or the like 19 may be threaded therethrough without 100 difficulty and uncomfortable projections are avoided on the inside of the garment.

The garment as shown in the drawings may be slipped on over the head of the wearer and provides a three-piece garment 105 in the form of a unit in which all unnecessary layers of material have been eliminated. After the garment is in place on the wearer the flap 13 is buttoned in position and if the section 5 is to be worn as a corset cover the 110 same is gathered in at the waist line through the medium of the ribbon or the like 19.

The garment has only the two side seams 7 and includes no other seams excepting the seams 11 whereby the upper edges of the drawers 10 are secured to the petticoat; by 5 making the seams 11 in the form of hem-stitching or the like the same may be utilized to add to the attractiveness of the garment. The latter is extremely simple in construction, is highly attractive in appearance 10 and combines three individual undergarments in one structure.

Various changes in the specific form shown and described may be made within the scope of the claims without departing 15 from the spirit of my improvement.

I claim:

1. An undergarment comprising an upper garment, a petticoat forming a depending continuation thereof and having a circular 20 bottom, drawers having upper and lower edges converging upwardly to central points and projecting downwardly and outwardly beyond the lower circular edge of the petticoat, said drawers being secured at their 25 outer portions near the lower edge of said

petticoat, seams converging upwardly from the points at which said drawers are secured to said petticoat whereby the upper edges of said drawers are fastened to the petticoat and a flap whereby opposite portions of said 30 drawers at the angles formed by the lower converging edges thereof are detachably connected together.

2. An undergarment comprising an upper garment, a petticoat, drawers, seams converging upwardly from the sides of the garment to the center thereof in the region of the waist line, the upper edges of said drawers terminating along said seams whereby double thicknesses of material at the hip 35 portions of the garment are avoided, a flap permanently secured to the lower edge of said drawers at an intermediate point and coöperating devices on said flap and drawers whereby the front and back portions of the 40 lower edge of the latter are detachably connected together.

In testimony whereof I have hereunto set my hand.

MEYER ZIMRING.
